UNITED STATES PATENT OFFICE

IRVING R. HIPPENMEYER, OF WAUKESHA, WISCONSIN, ASSIGNOR TO THE CREAMERY PACKAGE MFG. COMPANY, OF CHICAGO, ILLINOIS, A CORPORATION OF ILLINOIS

UNLOADING MECHANISM FOR BOTTLE WASHERS

Application filed July 18, 1927. Serial No. 206,483.

The invention relates to bottle washing apparatus, more particularly of the type having a series of travelling bottle pockets which carry the bottles over washing and rinsing jets.

The object of this invention is to provide improved unloading mechanism which automatically discharges the treated bottles from the pockets and places them upon a conveyor ready to be conducted to the filling machine.

Other objects and advantages will be apparent in the following description of a preferred embodiment of the invention which I have selected for illustration in the accompanying drawings. It will be understood however, that changes in form, construction and arrangement may be made by those skilled in the art without departing from the scope of the invention as expressed in the appended claims.

Referring to the drawings, Figure 1 represents a plan view of an end portion of a bottle washing machine, illustrating a portion of the series of bottle pockets and their supporting belt moving in a horizontal plane, together with my improved unloading mechanism.

Fig. 2 is a side elevation of the portion of the machine represented in Figure 1.

Fig. 3 is an end elevation of the same.

Fig. 4 is a fractional view in side elevation of a portion of the unloading mechanism.

In the drawings, the reference numeral 1 indicates upright frame members supported upon suitable base members 2 and carrying at their upper ends the top frame members 3. Within the substantially rectangular area enclosed by the upper frame members, are a pair of sprockets 4 and 5, mounted upon upper shafts 6 and 7 having suitable bearings supported upon the frame structure. Operatively engaged with the sprockets 4 and 5 is an endless conveyor belt preferable of link construction as indicated at 8. Outwardly spaced from the conveyor chain 8 is a stationary rail 9 mounted on the frame structure in any suitable manner, that herein illustrated comprising the supporting columns 10. Spaced from the end portion of the rail 9, and supported outwardly therefrom by the

extended frame members 11 and 12, is a conveyor belt 13 mounted upon a pair of rotating drums 14 and 15 and having the intermediate portion of its run resting upon a stationary table 16 having an inwardly and downwardly curved apron 17.

A series of bottle pockets 18, having open lower ends and adapted to receive individual bottles in inverted position, are supported upon the conveyor chain by means of a hinged connection including a laterally extending bracket 19 formed on the respective pocket structures and pivoted to suitably constructed links in the conveyor chain, the pivotal axis being horizontal. The opposite sides of the respective bottle pockets are provided with similar laterally extending brackets upon which are mounted rollers 20 which bear upon the upper side of the rail 9 and normally maintain the pockets in vertical position.

A section of the end portion of the rail 9 is separated, as indicated at 21 and 22, from the adjacent portions of the rail. The separated portion 23 of the rail is mounted on a plurality of brackets 24 each of which is pivoted on a shaft 25 having suitable bearings in the frame structure. The brackets 24 are continued inwardly and provided with reversely curved portions 26. The latter are provided at their upper extremities with a cross bar 27 extending laterally adjacent the inner sides of the bottle pockets 18. Mounted on the shaft 25 is an operating crank lever 28 which is pivotally connected with a rod 29, the latter being pivoted at its lower end upon one arm of a centrally pivoted lever 30 mounted on a gear housing 36.

The opposite arm of the lever 30 is provided with a roller 31 operatively bearing upon a rotating cam member 32 mounted upon a shaft 33. The latter is actuated by means of a worm gear 34 and worm 35 positioned within the housing 36. The worm 35 is mounted on a shaft 37 extending outwardly of the housing and being provided with a pulley 38 having belt connection with a motor 39.

The shaft 35 is also provided with a rigidly mounted crank 40 upon which is pivoted a link 41 oppositely pivoted to a rocker arm 42

freely mounted on a stub shaft 43 having suitable support in a structure 44 mounted on the frame. A ratchet wheel 45 is mounted on the shaft 43. The rocker arm 42 carries a dog 46 which engages within the ratchet notches of the wheel 45 and effects the intermittent rotation of the ratchet wheel. A bevel gear 47 rotating in fixed relation to the ratchet 45 is in mesh with a pinion 48 secured to the sprocket supporting vertical shaft 7.

The housing shaft 33 carries outwardly of the wall of the housing a sprocket upon which is mounted a chain belt 49 in driving engagement with a sprocket mounted on a shaft 50 having suitable bearings secured upon the frame members and extending outwardly beneath the upper run of the conveyor 13. Upon the latter shaft is mounted the driving drum 15 upon which the conveyor is end- 20 wardly supported.

Between the upper and lower runs of the conveyor 13 is a horizontal shaft 51 mounted in suitable bearings supported from the table 16. The shaft 51 has secured thereto a pair of goose-neck shaped arms 52 and 53 upon which are secured a cross bar 54, the latter supporting a slide plate 55. The shaft 51 is operated by means of a crank 56 secured thereto, at the outward end of which is pivoted a connecting rod 57 of which the inner end is secured to a strap 58 operatively mounted about an eccentric 59 secured to the sprocket shaft 7.

From the foregoing description it will be observed that all of the parts of the operating mechanism are interengaged in timed relation to effect the operating cycles hereinafter described.

As the bottle pockets 18 are advanced through the machine with an intermittent motion effected by the ratchet wheel 45 operated by the reciprocating dog 46 and transmitting intermittent rotation through the gears 47 and 48 and the sprocket 5, limited groups of pockets, herein illustrated as four, are successively positioned above the pivoted section 23 of the rail 9. The conveyor chain is at rest during the reverse movement of the dog 46, and by the operation of the cam 32, the brackets 24 supporting the section 23 of the rail are lowered about the shaft 25, and the pockets 18 permitted to swing by gravity about their hinged axes on the conveyor chain. Should any of the pockets fail to drop with the lowering of their under support, the cross bar 27 carried by the upper arms of the brackets strike the pockets laterally and force them downwardly. The lowered positions of the pivoted rail section and bottle pockets are illustrated in Fig. 4. In this figure also the slide plate 55 is shown to be in the position assumed in timed relation to the lowering of the bottle pockets, so that the bottles carried in the pockets slide out of the latter upon the slide plate and stop in abutment with the

curved apron 17 of the outer conveyor table 16. The continued movement of the cam 32 returns the rail section 23 and the bottle pockets 18 to normal position, while at the same time the eccentric 59 operates to rotate the shaft 51 and raise the slide plate 55 into vertical position, carrying therewith the discharged bottles and placing them in upright position upon the conveyor 13, by which they are conducted away to suitable mechanism usually positioned adjacent the washer for filling the washed bottles.

It will here be apparent that the bottles after having received the washing and rinsing treatment common to such machines, are automatically discharged and delivered to the filling machines without being handled manually, this automatic discharge being accomplished by a simple synchronized mechanism of open construction, readily accessible for maintenance and repair.

I claim as my invention:

1. In a bottle washing apparatus, an intermittently operable belt, a series of bottle pockets having lateral hinged attachment to said belt, a stationary track adapted to support said pockets in upright position, said track having a separable section adapted to be lowered whereby a group of bottle pockets thereby supported may be lowered to invert said pockets, and a bar mounted in rigid relation to said movable section of track and adapted to engage said pockets to force them down following the lowering of said sections of track.

2. In a bottle washing apparatus, an intermittently operable belt, a series of bottle pockets having hinged attachment at one side thereof to said belt, a stationary track affording opposite lateral support for said pockets in upright position, said track having a separable section, pivoted brackets supporting said section and adapted to lower said section and thereby lower a group of bottle pockets supported thereon, said hinged brackets having rigid arms extending adjacent said bottle pockets oppositely to said section of track, and a bar supported by said arms adapted to engage said pockets to swing them about their hinged attachment with the lowering of said section of track.

In testimony whereof, I have hereunto affixed my signature.

IRVING R. HIPPENMEYER.
